US0D1096420S

(12) **United States Design Patent** (10) **Patent No.:** **US D1,096,420 S**
(45) **Date of Patent:** **** Oct. 7, 2025**

(54) **CONTAINER WITH HOLDER**

(71) Applicant: **Umbra LLC**, Buffalo, NY (US)

(72) Inventor: **Sung Wook Park**, Toronto (CA)

(73) Assignee: **Umbra LLC**, Buffalo, NY (US)

(**) Term: **15 Years**

(21) Appl. No.: **29/959,471**

(22) Filed: **Aug. 26, 2024**

(51) LOC (15) Cl. **09-01**

(52) U.S. Cl.

USPC **D9/532**; D9/501; D6/523

(57) **CLAIM**

The ornamental design for a container with holder as shown and described.

DESCRIPTION

FIG. 1 is a top-right perspective view of a container with holder of the present invention;

FIG. 2 is a front elevation view of the invention shown in FIG. 1;

FIG. 3 is a rear elevation view of the invention shown in FIG. 1;

FIG. 4 is a left side elevation view of the invention shown in FIG. 1;

FIG. 5 is a right side elevation view of the invention shown in FIG. 1;

FIG. 6 is a top plan view of the invention shown in FIG. 1; and,

(Continued)

FIG. 7 is a bottom plan view of the invention shown in FIG. 1.

1 Claim, 4 Drawing Sheets
